METHOD OF MANUFACTURING BLANKS OF ARTICLES OF FELT AND AUTOMATIC MACHINE THEREFOR

Marcel Casse, Essonne, France

Application May 3, 1955, Serial No. 505,753

Claims priority, application France May 5, 1954

22 Claims. (Cl. 28—72.3)

The present invention relates to the manufacture of blanks of fibres for felt articles and more particularly to the production of hat blanks or bodies of fur or hair and blanks of other articles of fibre, for example glass fibre.

For ease of description, reference will be had herein-after only to fibres in the manufacture of the articles, but it must be understood that the scope of the invention is not intended to be limited to the use of fibres, since it is clear that hair or fur may be used instead of the latter.

Conventional methods of manufacturing hat bodies and other blanks comprise a first or forming operation followed by a second or hardening operation.

The forming consists in depositing the fibres, fur, hair or the like on a perforated support or hat form whose shape corresponds to that of the blank to obtain and through which is drawn a current of air. The fibres once deposited on the form, are sprayed with hot water. The blank obtained is very fragile, for the fibres merely adhere together owing to the action of the hot water. They have not yet been subjected to any felting operation.

A first felting is usually not effected until during the following operation, namely the hardening, which starts the agglomeration and interlacing of the fibres forming the felt cloth. The hardening is considered completed when each fibre is engaged at both ends in the mass of other fibres and that this mass of fibres has such cohesion as to allow its manipulation and to be capable of undergoing without tearing the subsequent felting operations.

Hardening is always a very delicate operation, since it is carried out after the blank has been removed from its perforated forming support, this blank being held flat between rolls which subject it to a relatively rough treatment. This hardening can only be carried out by very skilled operators.

Further, as concerns the material, the two consecutive operations of forming and hardening require two machines: a forming machine and a hardening machine.

The forming machines of known type are operated by two operators; one of the operators weighs the fibres and spreads them over a feed belt, the other effects several operations comprising opening the doors of the forming vessel or vat, spraying, removing and inverting the perforated support, and positioning the second support. Some of these operations require fairly considerable physical effort.

The spraying device is usually disposed inside the forming vessel, with consequent disadvantages. This device is a hindrance inside the vessel and the moisture introduced in the latter and the moisture on the device itself results in a loss of fibres and formation of defects in the hat bodies or other blanks.

The two doors usually supplied in the vessel only occupy about one third of the wall of the vessel. The opening they provide is hardly sufficient for handling the hat former cones or other perforated supports, this handling being, furthermore, rendered difficult even outside the machine by the presence of the open doors.

2

Finally, the manual handling of the doors, the cones or other perforated supports, the removal of the formed blank from the perforated supports, the operation of the spraying valves, are simple but troublesome requirements.

5 Automatic forming machines have been proposed but generally they comprise very complicated, delicate and incomplete mechanisms.

The purpose of the invention is to remedy the various disadvantages of known methods and machines.

10 A principal object of the invention is to provide a method of manufacturing blanks of fibres and in particular hat bodies or blanks of fur, hair or fibres in which the forming operation, i.e., the deposit of the fibres on a perforated hat former, and the hardening operation, i.e. the felting of these fibres, are carried out simultaneously.

The combination of the forming and hardening operations permits eliminating the usual very delicate hardening operation following the forming operation thus affording

20—an economy in very skilled manpower usually necessary for this hardening operation—or at least considerably reducing this hardening operation, if it must be retained, and carrying it out without harming the blank, which is already more firm owing to the hardening operation effected during the forming operation.

Another object of the invention is to provide a forming machine permitting application of the above-mentioned method.

Another object of the invention is to provide a forming 30 machine whose openable forming vessel or vat is so arranged as to permit obtaining a very large opening which considerably facilitates the introduction and removal of the cones or other perforated supports.

Another object of the invention is to provide a forming 35 machine in which the spraying device can be moved away from the forming vessel so that it does not moisten the interior thereof outside the spraying periods, does not hinder the forming operation and does not retain the hair, fur or other fibres.

40 Another object of the invention is to provide a forming machine which permits a very rapid replacement of the perforated support which has just received a blank by another support for the following forming operation.

Further features and advantages of the invention will 45 be apparent from the ensuing description with reference to the accompanying drawings given merely by way of example and in which:

Fig. 1 is an elevational and partially sectional view of a forming machine embodying the invention, more particularly provided for the forming and hardening of 50 hat blanks or bodies;

Fig. 2 is a plan view thereof, partially in section;

Fig. 3 is a detailed plan view of two switches and their operating member connected to the support, these switches being provided for the perforated forming cones and the 55 driving motors adapted slowly to rotate said cones when they are inside the vessel;

Fig. 4 is a partial vertical sectional view of the machine on an enlarged scale relative to that of Fig. 1;

Fig. 5 is a vertical sectional view of the support for 60 the spraying device in its withdrawn position;

Fig. 6 is a vertical sectional view taken along line 6—6 of Fig. 2 of the device supplying hot water to the spraying device;

Fig. 7 is a horizontal sectional view taken along line 65 7—7 of Fig. 6;

Fig. 8 is an elevational view on an enlarged scale relative to that of Fig. 1 of the device supplying hairs, fur or fibres;

Fig. 9 is a block diagram of the electrical connections;

70 Fig. 10 is a diagram of the switchbox for the motor adapted slowly to rotate one of the perforated cones, and

Fig. 11 is a diagram of the switchbox for one of the other motors.

This machine is more particularly intended for the manufacture of hat bodies and in order to render the description more clear reference will be had in the ensuing description only to hat bodies and perforated cones. However, it must be understood that this machine is equally applicable to the production of objects of any other form provided that the perforated cones are replaced by perforated supports having a form corresponding to that of the objects to be obtained.

This machine comprises, disposed on a fixed stand A, a forming station I and a station II for receiving the hat bodies at which station each formed hat body is separated from the perforated cone on which it was formed.

Fixed on the stand A is a movable support B adapted to support two perforated forming cones 1 and 1^a and bring them in succession and alternately to the station I and to the station II, the cone, such as the cone 1, situated at the station I being upright, its base being lowermost, whereas at the station II the cone 1^a is inverted. The support B is moved by a mechanism C.

On the support B, each cone 1 or 1^a is combined with a driving mechanism such as D which is adapted to impart to this cone, firstly, a slow rotary movement about its axis and, secondly, a rapid vibratory movement (having a frequency between 1,000 and 3,000 vibrations per minute and an amplitude of the order of 1 mm.), the latter being adapted to effect all or part of the hardening operation.

Provided at the station I is a fan E adapted to produce a down draft of air inside an openable forming vessel or vat F.

This vessel F is combined with a spraying device G which is capable of occupying two positions, in one of which it is disposed outside the vessel and in the other it is disposed at G¹ (Fig. 1) in an operative spraying position inside the vessel. The vessel E is also combined with a feed device H supplying fur, hair or other fibres.

The various above-described devices are actuated by a number of electric motors connected to various control devices forming the electro-mechanical equipment I shown in Fig. 9.

The machine operates in the following manner:

With the cone 1 in position, the feed device H pours fibres into the vessel F when the latter is in its closed state and, under the action of the current of air travelling in the direction of arrows f¹ produced by the fan E, the fibres are deposited in a layer O on the cone 1. The mechanism D imparts to the latter, firstly, a slow rotary movement which permits an even distribution of the fibres over the entire surface of the cone, and, secondly, a high-frequency vibratory movement of small amplitude which effects the hardening operation.

When the work O has been fully deposited on the cone 1, the vessel F is opened and the spraying device G, which occupies the operative position G¹, sprays the work O with hot water. Thereafter, the support B substitutes the cone 1^a for the cone 1, the cone 1^a being placed at station I, whereas the cone 1 provided with the hat body O takes up an inverted position as station II, where the body becomes detached from the cone, under the effect of the continued vibrations, and is received on a horizontal table supported by the stand A.

A detailed description will now be given of the devices A to I of the machine illustrated in the drawings.

(a) Stand A (Figs. 2, 3 and 4)

This stand comprises a frame 3 reinforced by a number of cross-members 4. It carries a number of uprights, namely an upright 5 carrying a reception table 2, two twin uprights 6 carrying the movable support B for the cones 1, 1^a, and four uprights 7 carrying the feed device H and a part of the mechanism adapted to actuate the vessel F and the spraying device G.

(b) Movable support B for the cones 1, 1^a

The two uprights 6 (Figs. 1 and 4) braced by a cross-member 8, carry a tubular column 9 which has a vertical axis TT and is rigidly secured to this cross-member 8. Fixed at the upper end of the column 9 and coaxial therewith is a bevel gear 10. This fixed bevel gear 10 meshes with two bevel gears or pinions 11 and 11^a rotatably mounted on a horizontal shaft 12 having an axis UU (Fig. 2). This shaft is carried by a sleeve 13 fixed to the upper end of a vertical shaft 14 which is capable of being rotated about the axis TT through about 90° by the mechanism C. Keyed to an extension from each of the two gears 11 and 11^a is a rigid arm 15 or 15^a on which is fixed a flat-shaped housing 16 or 16^a which forms the support for the cone 1 or 1^a.

The support unit comprising the members 16, 15, 12, 15^a and 16^a is substantially in the form of a Z, the two housings 16 and 16^a being transversely offset and slightly oblique relative to one another. This support is capable of pivoting, firstly, about the vertical axis TT of the column 9, and, secondly, about the horizontal axis UU of the shaft 12.

The rotation through about 90° of the shaft 14 about the vertical axis TT due to the fact that the gears 11 and 11^a mesh with the fixed bevel gear 10, is accompanied by a rotation through slightly less than 180° of the arms 15 and 15^a about the horizontal axis UU. This ensures the passage of the cones 1 and 1^a from the station I to the station II and vice versa. The mechanism C rotates the shaft 14.

(c) Mechanism C (Figs. 1, 2 and 4)

Keyed at 17 to the vertical shaft 14 adjacent the lower end thereof is a crank 18 on which is pivotably mounted, by means of a vertical pin 19, a cranked connecting rod 20. This connecting rod is pivoted at its other end to the crank-pin 21 of a crank-disc 22 which is rigid with a vertical shaft 23 journaled in a housing 24 attached to the stand A. Keyed to this shaft 23 is a worm wheel 25 meshing with a horizontal worm gear 26 whose shaft is connected, by a pulley 27, a belt 28 and another pulley 29, to the shaft 30 of an electric motor M¹.

Each cone, 1 or 1^a, when it is at the forming station I (where it is brought by the device B driven by the mechanism C just described), is subjected to a slow rotary movement about its axis and a rapid vibratory movement by the mechanism D which will now be described.

(d) Driving mechanism D for the cone, 1 or 1^a, at station I (Figs. 1, 2 and 4)

Fixed to the upper face of the flat housing 16 is a ring 31 disposed between a pulley 32 and a ring 33 which are fixed together and bear against opposite sides of the ring 31 through the medium of balls or rollers 34 and 35.

The pulley 32 comprises a hub 36 connected to the rim of the pulley by a number of radial arms 37. This pulley may be rotated slowly, for example one rotation per minute, by a motor M² through the medium of a speed reducer 38 (Fig. 1), a pulley 39 and twin belts 40 (Fig. 4) engaged in grooves formed in the pulley 32.

On the ring 33, fixed with respect to the pulley 32, is fixed, through the medium of a sealing collar or cylinder 41 of rubber or the like, a flat ring 42 on which is disposed the corresponding perforated cone, 1 or 1^a. For the purpose of rotating the ring 42 and the cone 1 by means of the pulley 32, connections are provided between the ring 42 and the radial arms 37 of the pulley 32, these connections being such that while imparting a rotary movement about the vertical axis VV to the cone, the latter is also capable of undergoing rapid vibratory movements of small amplitude. The connections are achieved by a number of short connecting pins 43. One of the ends of each pin is connected to one of the radial arms 37 by means of an yieldable coupling comprising, as known

per se, a combination of a sleeve 44 (Fig. 4) of rubber or the like which is subjected to radial compression between two concentric tubes 45 and 46. One of these tubes is rigid with the pin 43 and the other with the radial arm 47. The upper end of each pin 43 is fixed in similar manner to the ring 42.

This ring 42 and the cone 1 which it supports may be subjected to vibratory movements by the following device.

Several connecting rods 47, radially disposed relative to the axis VV, connect the ring 42 to a centre bearing box 48, the two ends of each connecting rod being pivoted to the ring 42 and the box 48 by means of vertical pins 49 and 50 with interposition of elastic bushings having rubber elements. The box 48 contains the outer ring 51 of a ball or roller bearing 52, the inner ring 53 of which is mounted on an eccentric journal 54 which has an axis WW parallel to the axis VV and constitutes a crank-pin at the end of a shaft 55.

This shaft 55, which is provided with a counterbalance 56 is journalled by means of two anti-friction bearings 57 and 58 in a box 59 rigid with the hub 36 of the pulley 32. Keyed to the lower end of the shaft 55 below the box 59 is a pulley 60 which is connected by a belt 61 to another pulley 62 (Fig. 2) keyed to the shaft of an electric motor M³. The latter therefore imparts, through the medium of the crank-pin 54 and the connecting rods 47, a rapid vibratory movement to the ring 42 and to the perforated cone 1, this movement being possible, notwithstanding the connection of the ring 42 to the pulley 32, owing to the yieldable connections between the pins 43, the collar 41 and the pulley 32.

The amplitude of the vibrations is equal to twice the value of the throw *e* of the axis WW relative to the axis VV, and as this throw is of the order of 0.5 mm., the amplitude of the vibrations is in consequence of the order of 1 mm.

The mechanism D is completed by a dome-shaped cover 63 which covers the central part of the mechanism and includes openings, such as shown at 64, for the free passage of the connecting rods 47 and the belt 61. Resting on the cover 63, through the medium of a number of uprights 65, is a circular convex plate 66, situated substantially midway of the top and bottom of the perforated cone 1.

At the station I the housing 16 containing the mechanism D rests, through the medium of a rubber sheet 67, on an upper horizontal flange 68 forming part of the fan E.

(e) *Fan E*

The flange 68 forms part of a member 69 connected by arms or webs 70 to a cylindrical tube 71. Attached to a horizontal plate 72 of this tube 71 is a housing 73 which supports, through the medium of two anti-friction bearings 74 and 75, a vertical shaft 76. This shaft carries at its upper end an axial fan wheel 77 whose blades 78 extend into the annular space provided above the tube 71 and between the latter and the annular member 69.

The lower end of the shaft 76 carries a pulley 79 which is connected by belts 80 to a pulley 81 keyed to the shaft of a motor M⁴. A discharge scroll or pipe 82 surrounds the tube 71 and comprises an outlet 83. This discharge pipe and the tube are fixed to the stand A.

The air drawn in by the fan E attains the forming station I through the upper opening of the vessel F, which will be described below. Thereafter, it traverses the cone 1 in the direction of arrows *f*¹, enters the annular space between the flange 68 and a solid plate 84, fixed above the central part of the fan, and is then pumped through the pipe 82 whence it is discharged to the atmosphere through the outlet 83.

(f) *Forming vessel F (Figs. 1 and 2)*

This vessel is of revolution about the vertical axis VV and preferably comprises, in vertically aligned adjacent

relationship, an upper downwardly flared conical portion, a long upwardly flared conical portion, a short upwardly flared conical portion having an apex angle greater than that of the last-mentioned portion, and a lower cylindrical portion. This vessel is composed of two half-shells 85 and 86 every horizontal section of which is substantially semi-annular in shape. Each of these half-shells comprises a strong sheet of metal reinforced by a number of arcuate straps, such as those shown at 87 and 88, and two flat members 90 and 91 extending along the two longitudinal edges.

In the closed position of the vessel, the two half-shells 85, 86 almost touch one another along the members 90 and 91 which are very near to one another in the vertical median plane XX (Fig. 2). Each of these half-shells is heated exteriorly by a nest of tubes 92.

The two half-shells are pivotably mounted on a shaft 94, having a vertical axis XX, by means of a lower plate 95 and an upper plate 96, the two plates pertaining to each half-shell being connected to the latter by two horizontal strips 97 and 98 which are braced by a vertical strip 99.

Owing to the position of the axis YY, in pivoting the two half-shells about the latter it is possible to bring them to the open positions shown in dot-dash lines at 85^a and 86^a (Fig. 2), which gives free and very wide access to the forming station I from the left side of the latter as seen in Fig. 2.

Pivotably mounted on the two lower plates 95 pertaining to the two half-shells, by means of vertical journals 100, are two telescopic connecting rods each of which comprises two elements 101 and 102 which a spring 103 tends to urge apart axially, thereby increasing the length of the connecting rod. Each of the latter is pivoted to one of two crank-pins 104 of a crank shaft 105. The shaft 105 is rotated by a motor M⁵ through the medium of a pulley 106, a belt 107, a second pulley 108 and a reducing mechanism including a worm gear 109 and a worm wheel 110 which is keyed to the shaft 105.

The crank-pins 104 on which the connecting rods are pivotably mounted are so disposed on the shaft 105 that for a rotation through 180° of the latter the two connecting rods are simultaneously subjected to a tractive force resulting in the opening of the vessel, whereas the following rotation through 180° subjects the connecting rods to a compressive force resulting in the closing of the vessel. The motor M⁵ is controlled, as will be described hereinafter, in such manner that it stops either when the two half-shells are brought together (position shown in full line in Fig. 2) or when they are separated to the maximum extent (position shown in dot-dash line 85^a, 86^a in Fig. 2).

Owing to the telescopic construction of the two connecting rods, the latter form a safety device. If, for example, the operator in charge of the machine fails to remove his arm from between the two half-shells when the latter are closing, the springs 103 become compressed and absorb the force which would otherwise have been applied to his arm.

The shaft 105 is also adapted to control the spraying device G.

g. *Spraying device G*

The spraying device comprises (Figs. 1, 2 and 5) a tubular arm 111 which is cranked adjacent its lower end at 112 (Fig. 7) and has a horizontal extension 113 which is journalled in a bore 114 formed in a body 115 which is connected by a support 116 to a cross-member 117 (Fig. 1), connected to two of the uprights 7 of the stand. The arm is, furthermore, pivoted by a journal 118 (Fig. 7) to a bearing 119 connected to the member 115.

Connected to the arm 111 is the spray diffuser comprising a channel 120 (Figs. 1 and 5) which has a rectangular cross-sectional shape and is closed along its side

facing the station I by a plate 121 in which are formed several small apertures 122 for the outlet of hot water.

This spraying device G is capable of occupying two positions by pivoting about the axis ZZ of the journal 118 and bearing 114, namely: an inoperative position illustrated in full line in Fig. 1 in which this device is positioned outside the vessel F constituted by the two closed half-shells, and another position G¹, that is, the operative position shown in dot-dash line in Fig. 1, in which this device is ready for spraying.

The pivotal movements of the device G are controlled by the shaft 105 which carries, keyed to its lower ends, a cam 123 which co-operates with a roller 124 (Fig. 1) carried by a lever 125. The latter is pivoted to one of the ends of a connecting rod 126 (Figs. 1 and 5), the other end of this rod being pivoted at 127 to a crank 128 rigidly secured to the arm 111 of the spraying device G.

The latter is supplied with hot water by a distributing device controlled by an electric motor M⁶ (Figs. 1 and 2). The latter drives, through a pulley 129, a belt 130 and another pulley 131 (Fig. 6), a shaft 132 to which is keyed, inside a housing 133, a worm gear 134. The latter drives, through the medium of a worm wheel 135, a horizontal shaft 136. This shaft carries, outside the housing 133, a cam 136 against which a spring 138 urges a roller 139 whose spindle 140 is carried by a lever 141. The latter is pivotably mounted on a fixed pin 142. Pivotably mounted on pins 143 and 144, disposed on either side of the pin 142, are two rods 145 and 146. The latter extend through two packings 147 and 148 into a valve box 149 connected to the member 115.

The tube 113 communicates with a central chamber 150 in the valve box 149 through the conical portion 151 (Fig. 7). This chamber 150 communicates, firstly, with a connection 152 (Figs. 1 and 6) connected to a hot water supply pipe, the communication being controlled by an inlet valve 153; and, secondly, with an outlet or exhaust connection 154 connected with a drain or reservoir, the communication being controlled by a drain valve 155.

The rods 145 and 146 are disposed respectively below the inlet valve 153 and the draining valve 155. The length of these rods is such that when the lever 141 is horizontal, the two valves 153 and 155 rest on their respective seatings under the effect of gravity, and when this lever 141 is pivoted by the cam 137 in the direction of arrow f² (Fig. 6) the inlet valve 153 is raised by the rod 145 whereas the draining valve 155 remains closed, and vice versa.

(h) *Feed device H for hair, fur or fibres (Figs. 1 and 8)*

This device, which is disposed at the upper part of the forming device and is carried by uprights 7, comprises an inclined trough 156 which receives the amount of hair, fur or fibres corresponding to a hat body to be manufactured. Disposed at the lower end of this trough 156 are two feed rolls 157. The latter are rotated by an electric motor M⁷ through grooved pulleys 158, 159 connected by a belt 160 and a speed reducer 161, the driven shaft of the latter being keyed to one of the rolls 157. The different diameters of the grooves of the pulleys 158 and 159 permit varying the speed of the rolls 157 and the forming period in accordance with the supply of fur, hair or fibres.

The reducing gear train 162 is driven by one of the rolls 157 and drives a shaft 163 adapted to control the power supply to the motor M⁷, as will be explained hereinunder.

Disposed on the output side of the feed rolls 157 is a normal picker 164 the points of which are adapted to disperse the hair, fur or fibres. A brush 165 receives the latter and in turn projects them into a passageway 166. This passageway extends into the upper part of the vessel F through a notch 167 formed in each half-shell and the bottom of this passageway is provided with an

adjustable extension 168 by means of which it is possible to pour the hair, fur or fibres in the direction of arrow f³ (Fig. 1) substantially in alignment with the axis VV of the vessel.

5 A motor M⁸ (Fig. 1) drives the picker 164 and the brush 165 through two belts 169 and 170.

(i) *The electric motors, the control devices and their power supply (see in particular Figs. 9 and 10)*

10 It will be recalled that the machine is provided with ten motors. Further, for the purpose of illustration these motors are assumed to be three-phase motors.

The supply line 171 for the electrical equipment of the machine is connected by a main switch 172 to the three-phase conductors 173 to which the various motors are connected in parallel. These motors are divided into three groups.

15 The first group comprises the motors M³ and M^{3a}, vibrating the cones 1, 1^a, M⁴ driving the fan and M⁸ driving the picker 164 and the brush 165; these motors are directly connected to the conductor 173 and continuously rotate as soon as the switch 172 is closed.

20 The second group of motors comprises the motors M², M^{2a}, adapted slowly to rotate the cones 1 and 1^a. The power supply to these motors is controlled by two switch boxes N² and N^{2a}, the latter being under the control of two operating push buttons m² and m^{2a}; the unit comprising N² and m² is shown by way of example in Fig. 10, the unit corresponding to the motor M^{2a} being identical. Fig. 10 shows at 174 the three conductors adapted to connect with the conductors 173 controlled by the main switch 172. These conductors 174 are connected to three terminals 175, 176 and 177 which may be connected respectively by blades 178, 179 and 180 to three terminals 181, 182 and 183 which are connected by the conductors 184 to the terminals of the motor. The three blades 178, 179 and 180 are connected by a connection 185 having a control blade 186 which is pivoted at 187 and co-operates with an electromagnet comprising an armature 188 and a coil 189. The latter is closed on the terminals 175, 176 on one of the phases of the supply current by the conductors 190 and 191 leading to the two terminals 193 and 194 of the switch box. These two terminals are connected by two conductors 195, 196 to the two studs 197, 198 of a switch m² comprising a start push button normally held separated from the two studs by a spring 199. This push button is moved in the direction to close the circuit by the portion 200 of a double cam 200—200^a (Figs. 1, 2 and 9); the portion 200^a pertains to the switch m^{2a} of the motor M^{2a}. This cam is fixed to the lower end of the pivotable shaft 14 of the movable support B.

25 As this support is rotated by the mechanism C through 90° and as the two cams 200 and 200^a are diametrically opposed, it is sufficient that the two switches m² and m^{2a} be disposed on two radii angularly spaced 90° apart relative to the axis of the shaft 14 to obtain that each of these switches, m² or m^{2a}, be closed by the corresponding cam, 200 or 200^a, when the corresponding cone, 1 or 1^a, is at the forming station I and opened when this cone is at the unloading station II.

30 When the switch m² (or m^{2a}) is closed, the coil 189 is energized, the blade 186 is attracted and current is caused to be supplied to the corresponding motor M² (or M^{2a}).

35 The cone, 1 or 1^a, is thus rotated slowly about the vertical axis VV (Fig. 1) when it is at station I; it ceases to rotate at station II. However, at both stations the cone continues to vibrate owing to the continued power supply to the corresponding motor M³ or M^{3a}.

40 The third group of motors comprises the following: motor M⁷ driving the feed rolls 157, motor M⁵ controlling the opening and closing of the half-shells and the position of the spraying device G, motor M⁶ controlling the supply of the spraying water, and motor M¹

controlling the mechanism C adapted to interchange the cones by moving their support B.

These motors are combined with switch boxes N⁷, N⁵, N⁶ and N¹ respectively, each of which is provided, as will be explained hereinunder, with at least one start push button and a stop push button. These buttons are combined with cams driven by shafts which are themselves driven by the above-mentioned motors, so that each motor stops itself and simultaneously starts up the following motor in the order indicated above, i.e., M⁷, M⁵ (opening of the vessel), M⁶ and M¹, the motor M¹ ensuring, at the same time as its own stoppage, the starting up of the motor M⁵ for closing the vessel, this motor ensuring, when it stops itself a second time, the starting up of the motor M⁷, so that the operational cycles, which commence with supply of power to this motor M⁷, may continue without interruption so long as the switch 172 remains closed.

Before describing in detail the various connections which permit obtaining the continuous operation mentioned above, reference will be had to Fig. 11 which shows one of the switch boxes of one of the motors of the third group, for example, the switch box N¹ pertaining to the motor M¹.

This switch box N¹ is very similar to the switch box N² described above. It comprises all the elements of the switch box N² and notably the start switch m¹ having a push button. It further comprises a third output terminal 201, the terminals 201 and 193 being connected by conductors 202 and 203 to the studs 204 and 205 of a stop switch a¹ which is normally closed by a spring device. One of the ends of the coil 189 is connected in parallel with the terminal 194 directly and with the terminal 201 through an auxiliary switch having a blade 206 which is actuated at the same time as the blades 178-180 of the main switch.

This switch box with its two switches m¹ and a¹ is of the known type and it has only been illustrated for the purpose of description. Its operation is simple; by pushing the start button the electromagnet 188, 189 is temporarily energized and attracts all the blades, which results in closure of the motor circuit and the circuit of the coil 189 through the circuit 175, 193, 202, the studs 204 and 205 of the normally closed stop switch a¹, the terminal 201, the closed auxiliary switch 206, the coil 189 and the terminal 176.

The main switches, having blades 178 to 180, and the auxiliary switches 206 remain closed until the above-mentioned control circuit is opened by depressing the stop button of the switch a¹.

With reference to Fig. 9, the motor M⁷ comprises a stop switch a⁷ which has a push button and is connected, as mentioned above, to the switch box N⁷, and two start switches m⁷ and n⁷ connected in parallel. The switch n⁷ is, in the illustrated embodiment, a hand operated start switch. In a forming machine automatically combined with a fibre weighing device it could be controlled or actuated by the motor for the latter so as to be automatically closed as soon as the weighing device has supplied the trough 156 with the required weight of fibre for forming a hat body. The other switch m⁷ is controlled or actuated by the motor M⁵.

With respect to the latter, it comprises a start switch m⁵ controlled by the motor M⁷ and a stop switch a⁵ which is directly controlled by the motor M⁵.

The motor M⁶ comprises a start switch m⁶ controlled by the motor M⁵ and a stop switch a⁶ which is directly controlled by the motor M⁶.

The motor M¹ comprises a start switch m¹ controlled by the motor M⁶ and a stop switch a¹ directly controlled by the motor M⁶. Further, an auxiliary start switch n⁵ for the motor M⁵ is controlled by the motor M¹.

The various controls mentioned above are arranged in

the following manner. The stop switch a⁷ of the motor M⁷ is controlled by a first cam 207 which has a single boss 208 and is keyed to the shaft 163 connected by a speed reducing train 162 (Fig. 8) to one of the feed rolls 157.

The same shaft 163 drives a second cam 209 also provided with a single boss 210 and adapted to close the start switch m⁵ of the motor M⁵ controlling the half-shells. The switches a⁷ and m⁵ are shown in Figs. 1 and 8.

The speed reducing train 162 is so arranged that the shaft 163 effects one rotation for each operational cycle and the bosses 208 and 210 are so disposed that the boss 210 closes the switch m⁵ as soon as the boss 208 opens the switch a⁷. The shaft 163 rotates in the direction of arrow f⁴ (Fig. 9); the cams are therefore shown at the start of a feed cycle.

The motor M⁶ for opening the two half-shells 85 and 86 of the vessel F acts on these shells and on the spraying device G through the medium of a shaft 105 (Figs. 1 and 2) as explained above. Keyed to this shaft 105 are four cams: cam 211 having one boss 212, cam 213 having two bosses 214 and 215, cam 216 having a single boss 217, and cam 218 having a single boss 219. For reasons

of clarity in Fig. 1, the two cams 213 and 216 have been shown coincident, the boss 217 being combined with the cam 213. The shaft 105 is such that it effects one rotation in the course of one operational cycle of the machine, i.e. half a rotation for opening the half-shells and

half a rotation for closing the latter. The cam 211 having a single boss 212 co-operates with the start switch m⁶ for the motor M⁶ controlling the spraying. The cam 213 having two bosses 214 and 215 controls the stop switch a⁶ of the motor M⁶. The cam 216, or at least the boss 217, controls the start switch m⁷ for the motor M⁷. The cam 218 having a single boss 219 constitutes a safety device which only permits the motor M⁷ to be started by the push button n⁷ and to cause supply of fibres when the two half-shells 85 and 86 have been brought together.

The various bosses are so arranged that the motor M⁶ pertaining to the spraying device is started up by the boss 212 at the moment when the boss 214 of the cam 213 stops the motor M⁶ in the position corresponding to the open position of the half-shells. Further, the arrangement of these bosses is such that the boss 217 closes the start switch m⁷ for the motor M⁷ at the moment when the boss 215 causes stoppage of the motor M⁶, the vessel F being closed.

The shaft 105 rotates in the direction of arrow f⁵ and effects one rotation per operational cycle.

The motor M⁶, the starting of which is controlled by the switch m⁶ controlled by the motor M⁵, drives the shaft 136 through one rotation in the direction of arrow f⁶ for each operational cycle. The cam 137 which actuates, by means of the lever 141, the valves 153 and 155 relating to the inlet and outlet of the hot spraying water, is mounted on this shaft 136. It will be observed that the switches a⁵, m⁶ and m⁷ are shown in Fig. 1. Keyed

to the same shaft 136 is a first cam 220 having a boss 221 adapted to actuate the stop switch a⁶ for the motor M⁶, and a second cam 222 having a boss 223 adapted to actuate the start switch m¹ for the motor M¹ which is adapted to change the cones.

The shaft 23, driven by the motor M¹, carries a cam 224 having two bosses 225 and 226 which are adapted to actuate, in turn, simultaneously the stop switch a¹ of the corresponding motor M¹ and the auxiliary start switch n⁵ for the motor M⁵ which is adapted to actuate the half-shells.

In order to render the block diagram shown in Fig. 9 more clear, the two switches a¹ and n⁵ have been separated from one another and the cam has been shown at two positions on the shaft 23.

The complete machine operates in the following manner:

It will be assumed that the machine is inoperative, the switch 172 being open.

A supply of fibres necessary for producing the work O is placed in the trough 156 on the input side of the feed rolls 157. As soon as the switch 172 is closed, the conductors 173 carry current and the four motors of the first group: M³ and M^{3a} which maintain the vibrations of the cones 1, 1^a, M⁴ driving the fan E, and M⁸ driving the picker 164 and the brush 165, are supplied with the current and rotate. They rotate throughout the successive operational cycles of the machine until the switch 172 is opened.

With regard to the motors M² and M^{2a} of the second group adapted slowly to rotate the cones 1 and 1^a, it will be recalled that they are supplied with power only when the switch m² or m^{2a} is closed by the cam 200 or 200^a at the moment when the corresponding cone is at station I for the forming operation.

With respect to the third group of motors which are interconnected by the above-described set of switches and cams, the machine may either be in a position corresponding to the beginning of an operational cycle or it may have been stopped in any other position.

The former case will be examined first. It will be assumed that the machine has been stopped at the end of an operational cycle, shown in Fig. 9, in which the switch n⁷ and the automatic starting switch m⁷ are open, both of which pertain to the motor M⁷ driving the feed device. This motor and the motors M⁵, M⁶, M¹ are all inoperative.

To start up a cycle of operations it suffices to depress the hand switch n⁷ which energizes the electromagnet 189 in the switch box n⁷ and the motor M⁷ is supplied with power and will continue to be supplied with power until this motor, through the medium of the cam 207, opens its own stop switch a⁷. The motor M⁷ drives the feed rolls 157 and the latter feed the fibres, previously deposited in the trough 156 towards the picker 164. The fibres pass between these feed rolls, are combed by the picker 164 and are projected by the brush 165 into the forming vessel F, the half-shells 85, 86 being in their closed positions.

The motor M⁴ of the fan drives the latter continuously and air is drawn through the upper part of the vessel F in the direction of arrow f⁴ and expelled through the outlet 83. The fibres, entrained by this current of air are deposited on the cone 1 and form the work O. As the switch m² is closed, the motor M² operates and imparts to the cone a slow rotary movement, and the motor M³, continuously supplied with power, imparts rapid vibratory movements of small amplitude to this cone.

As mentioned above, the slow rotation of the cone 1 ensures a perfect distribution of the fibres over the entire periphery of this cone and the rapid vibrations effect the hardening operation or at least the initial part of this operation.

The motor M⁷ driving the feed rolls drives, through the shaft 163, the two cams 207 and 209, and when this shaft has effected one rotation corresponding to the passage of the entire supply of fibres between the feed rolls, the boss 208 of the cam 207 opens the switch a⁷ and stops the motor M⁷, and the boss 210 of the cam 209 closes the switch m⁵ of the motor M⁵ and starts up the latter.

This causes, through the medium of the telescopic connecting rods, the opening of the vessel F, the two half-shells of which assume positions 85a and 86a (Fig. 2), whereas, through the medium of the cam 123 fixed to the shaft 185, the spraying device G is brought to position G¹ above the cone 1.

Meanwhile, as a result of a half rotation of the shaft 105 necessary for the opening of the vessel F and the positioning of the spraying device at position G¹, the boss 215 of the cam 213 causes the opening of the switch a⁵ and temporarily stops the motor M⁵. The half-shells remain

in their open position and the spraying device remains in its operative position G¹.

The cam 212 then closes the start switch m⁶ of the motor M⁶ which, through the cam 137, causes, initially, the raising of the inlet valve 153 (Fig. 6) permitting the admission of hot water through the connection 152, the chamber 150 and the pipes 151 and 113 (Fig. 7), the water attaining the arm 111 and the perforated spray diffuser 120. After the desired amount of spraying, the duration of which is governed by the shape of the cam 137 (Fig. 1), the valve 153 is closed and the exhaust valve 155 opened, permitting the evacuation of the water contained in the arm 111, the pipes 113 and 151 and the chamber 150.

In the course of the operation of these valves, the shaft 36 of the cam 137 also drives the two cams 220 and 222 and after the shaft 136 has effected one rotation in the direction of arrow f⁶, the boss 221 of the cam 220 opens the switch a⁶, which stops the motor M⁶ pertaining to the water supply, and the boss 223 of the cam 222 closes the switch m¹ of the motor M¹ adapted to change the cones.

The motor M¹, thus started up, rotates—through the medium of the crank-disk 22, the connecting rod 20 and the crank 18—the shaft 14 of the movable support B, which changes the positions of the cones 1 and 1^a. The cone 1 supporting the work O is positioned above the table 2 replacing the cone 1^a (Fig. 1) and the latter takes up its position at station I inside the vessel F which is still in its open position.

It will be observed that after the cones have changed position owing to the continuous supply of power to the motors M³ and M^{3a}, the cone which takes up position 1^a and still supports the work O continues to vibrate and the vibrations, which at station I had ensured the hardening operation now, at station II, serve to loosen the work O from the surface of the cone, this work falling without harmful effect onto the table 2.

In the course of changing the cones, the shaft 23 effects half a rotation in the direction of arrow f¹ and after this half rotation the boss 226 opens the switch a¹ which stops the motor M¹ and the same boss 226 of the cam 224 closes the switch n⁵ which starts up the motor M⁵ controlling the half-shells.

This motor M⁵ first shifts the spraying device from the operative position G¹ into the inoperative position G and then moves the two half-shells into their closed position. Meanwhile the shaft 105 driven by this motor effects a further half rotation which brings this shaft into the initial position shown in Fig. 9 in which the boss 214, in encountering the switch a⁵, stops the motor M⁵ and the boss 217 of the cam 216 temporarily closes the switch m⁷ of the motor M⁷, thus automatically commencing the following cycle of operations, provided the switch 172 is closed. The different cams actuating the switches and the latter are then in the positions shown in Fig. 9.

A further cycle of operations immediately follows the preceding one and permits forming a further hat body on the cone 1^a which has taken up the position of the cone 1 in the vessel F, provided that in the course of the preceding operational cycle the trough 156 had been supplied with a further supply of fibres.

If, by chance, the machine is stopped in the course of an operational cycle by opening the switch 172, all the parts remain in their respective positions and when the switch is once more closed the machine starts up, as at the beginning of an operational cycle, by the closure of the switch n⁷, an incomplete operational cycle being effected followed by a normal cycle.

As can be seen, the operation of the machine itself is entirely automatic provided the trough 156 is supplied with fibres. It is obvious that the forming machine may be combined with an automatic feed device which feeds successive supplies of the correct amount of fibres, these amounts being preferably variable. In this way an en-

tirely automatic installation is obtained (various devices have already been proposed for automatically feeding the fibres).

Although a specific embodiment of the invention has been described hereinbefore, it must be understood that the invention is not intended to be limited thereto since many modifications and changes may be effected therein without departing from the spirit of the invention or the scope of the appended claims.

In the illustrated embodiment the vibrations are imparted continuously to the cones 1 and 1a so that the action due to these vibrations continues until the hat body leaves the cone, but this mode of operation is not essential and it may be arranged that the vibrations be imparted to each cone only during a part of the operational cycle, for example before and during, or during and after the spraying operation.

Having now described my invention what I claim as new and desire to secure by Letters Patent is:

1. In a method of manufacturing blanks of fibres for felt articles, depositing fibres in a layer on the surface of a perforated former, imparting to the layer of fibres vibrations having a frequency of at least about 500 cycles per minute and amplitude of at least 0.5 mm. during the forming operation on the blank on the surface of a perforated support, whereby a hardening operation on the blank is effected.

2. Method of manufacturing blanks of fibres for felt articles which comprises the steps of forming said blank by depositing a layer of fibres on the surface of a perforated former, and then simultaneously spraying this layer and subjecting it to a first felting hardening consisting in imparting to the layer and to the former vibrations having a frequency of at least about 500 cycles per minute and amplitude of at least about 0.5 mm.

3. In a method of manufacturing blanks of fibres for felt articles, depositing fibers in a layer on the surface of a perforated former subjecting the layer of fibres to high-frequency vibrations of the order of 1,000-3,000 cycles per minute and of amplitude of the order of mm. during the forming operation whereby the layer of fibres is subjected to a hardening operation.

4. In a method of manufacturing blanks of fibres for felt articles depositing fibers in a layer on the surface of a perforated former, subjecting the layer of fibres to vibrations having a frequency of at least about 500 cycles per minute and amplitude of at least about 0.5 mm. during the forming operation on the blank on the surface of a perforated support, whereby the layer of fibres is subjected to a hardening operation, and continuing said vibrations during the removal of the blank from said perforated support, whereby to assist the removal of the blank.

5. In an automatic forming machine for forming blanks of fibres for felt articles, in combination: a stand, a support disposed on the latter, a rotatable ring disposed on the support, a first motor carried by the support for slowly rotating the ring, a second ring, a yieldable connection between the first ring and the second ring for imparting to the second ring the rotation of the first ring while permitting it to vibrate relative to the first ring, a perforated former fixed on the second ring for receiving a layer of fibres constituting said blank, and means carried by the support for vibrating the second ring and said former.

6. Machine as claimed in claim 5, wherein the first ring comprises a central hub and said vibrating means comprise: a second electric motor carried by the support, a shaft rotatably mounted in the hub and provided with an eccentric journal disposed exteriorly of the hub, a driving connection between the second motor and the shaft so that the latter is rotated at a higher velocity than the first ring, and several connecting rods pivoted to the second ring and to the eccentric journal for imparting to the second ring and to the perforated former

vibrations caused by the throw of the eccentric journal.

7. In an automatic forming machine for forming blanks of fibres for felt articles, in combination: a stand; a forming vessel comprising two half-shells pivoted on the stand outside the vessel, which is constituted by their reunion; a vertical tubular column fixed to the stand outside the vessel in a position substantially diametrically opposed to the pivot axes of the half-shells; a vertical shaft journalled in the column; a control mechanism connected to the shaft for imparting thereto intermittent pivotal movements; a horizontal sleeve rigidly secured to the shaft above the column; a bevel gear fixed to the upper end of the column below the sleeve; a horizontal shaft journalled in the latter from which it protrudes at each end; two bevel gear pinions fixed on the ends of this horizontal shaft and meshing with said bevel gear; two arms fixed to said ends of the horizontal shaft and extending in substantially opposite directions; a housing fixed cantilever fashion at the end of each arm; and a perforated former carried by the housing and adapted to receive a layer of fibres, the arms being so adapted and arranged that in the course of the pivotal movements of the vertical shaft the two formers are interchanged one of which assumes an upright forming position inside the vessel and the other is disposed outside the vessel in an inverted position for the purpose of removing the formed blank.

8. Machine as claimed in claim 7, comprising disposed on each housing: a rotatable ring provided with a hub; a first motor carried by the housing for slowly rotating the ring; a second ring on which is fixed the perforated former; a yieldable connection between the second ring and the first ring for imparting to the first ring and to the former the slow rotation of the first ring while permitting it to vibrate relative to the first ring; a second electric motor carried by the housing; a shaft rotatably mounted in the hub of the first ring and provided with an eccentric journal disposed outside the hub; a driving connection between the second motor and the shaft so that the latter is rotated at a velocity higher than that of the first ring; and several connecting rods pivoted to the second ring and to the eccentric journal for imparting to the second ring and to the perforated former vibrations resulting from the throw of the eccentric journal.

9. Machine as claimed in claim 8, wherein means are provided for permanently supplying power to the second electric motor, there being provided a switch controlling the power supply to the first motor, this switch being carried by the stand and being so disposed that the first motor is supplied with power only when the corresponding perforated former is in the forming position in the vessel, whereby the vibrations are permanently imparted to said former whereas it is subjected to a slow rotary movement only when it is in the vessel.

10. Machine as claimed in claim 7, wherein disposed below the vessel comprising the two half-shells is a suction fan the discharge pipe of which serves as a support for the housing carrying the perforated former which is in the forming position in the vessel, and a yieldable member carried by this discharge pipe being disposed between the latter and the housing.

11. In an automatic forming machine for forming blanks of fibres for felt articles: a stand, a forming vessel disposed on the latter and formed of two half-shells pivoted to the stand; a fibre feeding device disposed above the vessel and comprising rotatable rolls; a support for two perforated formers, this support being movably mounted on the stand for alternately disposing in the vessel in the forming position one and then the other of said formers; a spraying device movable between an operative position in the vessel for spraying the layer of fibres deposited on the former disposed within the vessel and an inoperative withdrawn position outside the latter; control means controlling the supply of spraying liquid to the

spraying device; four electric motors, the first of the latter driving said feed rolls, the second motor opening and closing the half-shells and moving the spraying device, the third motor controlling the supply of spraying liquid to the latter, and the fourth ensuring the movements of the movable support; start and stop switches for these motors and cams driven by the latter for actuating the switches in such manner that the motors are supplied with power in succession, each motor ensuring its own stoppage and ensuring the supply of power to the following motor, it being arranged to supply the motor controlling the half-shells with power twice in the course of a cycle under the control of two start switches controlled respectively by the motor driving the feed rolls and by the motor controlling the movements of the support for changing the perforated formers, and the motor controlling the half-shells also controlling through the medium of an auxiliary start switch the motor supply to the motor driving the feed rolls, this auxiliary switch being connected in parallel with a hand-operated start switch.

12. In an automatic forming machine for forming blanks of fibres for felt articles, the combination comprising a fibre-feeding device, a perforated former positioned to receive fibres from said device, means operatively connected to said former for moving it between an upright forming position and an inverted blank-removal position, and means operatively connected to said former for imparting thereto high-frequency vibratory movements of small amplitude in both of said positions of said former, whereby said vibratory movements effect a first felting of the fibres received by said former whereas said vibratory movements assist the removal of the blank formed on said former in said blank-removal position of the latter.

13. In a method of manufacturing blanks of fibres for felt articles, which comprises a blank forming operation on the surface of a support vibrating normally at a frequency of at least 500 cycles per minute and amplitude of at least 0.5 mm., effecting in the course of said forming operation a hardening operation of the blank which consists in imparting high-frequency vibrations of more than twice the frequency of the normal vibrations to said support.

14. In a method of manufacturing blanks of fibres for felt articles, simultaneously depositing fibres on a support, causing said support to effect a slow rotational movement and imparting to said support high frequency vibrations of 1,000-3,000 cycles per minute and of amplitude of about 1 mm. which vibrations cause said support to vibrate more than it would normally vibrate when it effects said slow rotational movement.

15. In a method of manufacturing blanks of fibres for felt articles, which comprises a blank forming operation on the surface of a cone shaped support vibrating normally at a frequency of at least 500 cycles per minute and an amplitude of at least 0.5 mm., effecting in the course of said forming operation a hardening operation on the blank which consists in imparting high-frequency vibrations of more than twice the frequency of the normal vibrations to said cone transversely of the latter which causes the cone shaped support to increase its vibrations during said forming operation.

16. In a forming machine for forming blanks of fibres for felt articles, in combination: a former adapted to receive a layer of said fibres, means for slowly rotating the former, and means for imparting to the former high frequency vibrations of small amplitude in the course of the rotation of the former so as to harden the layer of fibres.

17. In a forming machine for forming blanks of fibres for felt articles, in combination: a former adapted to receive a layer of said fibres, means for slowly rotating the former and means for imparting to the former high-frequency vibrations of small amplitude transversely of

the axis of rotation of the former so as to harden the layer of fibres.

18. In a forming machine for forming blanks of fibres for felt articles, in combination: a tapered former on which the blanks are formed, a forming vessel, means for blowing fibres into the forming vessel, an arm swingable about a substantially horizontal axis and on which the former is mounted throughout the operation of the machine, means for swinging the arm about said axis between a first position, in which the former mounted on the arm is located inside the forming vessel and is upwardly convergent and receives said fibres, and a second position in which the former mounted on the arm is located outside the forming vessel in a substantially inverted downwardly convergent position which facilitates removal of the blank formed thereon.

19. In a forming machine for forming blanks of fibres for felt articles, in combination: a first tapered former and a second tapered former on which formers the blanks are formed, a forming vessel, means for blowing fibres into the forming vessel, a first swingable arm and a second swingable arm on which the first and second formers are respectively mounted throughout the operation of the machine, means for swinging each arm about a substantially horizontal axis between a first position in which the former mounted thereon is located inside the forming vessel and is upwardly convergent and receives said fibres, and a second position in which the former mounted on the arm is located outside the forming vessel in a substantially inverted downwardly convergent position facilitating removal of the blank formed thereon, and a device controlling said means in such manner that the arms are swung in opposite directions and that the first former is located inside the forming vessel when the second former is located outside the forming vessel and vice versa.

20. In a forming machine for forming blanks of fibres for felt articles, in combination: a first tapered former and a second tapered former on which formers the blanks are formed, a forming vessel, a first swingable arm and a second swingable arm on which the first and second formers are respectively mounted, means for swinging each arm about a substantially horizontal axis between a first position in which the former mounted thereon is located inside the forming vessel and is upwardly convergent and receives the fibres, and a second position in which the former is located outside the forming vessel in a substantially inverted downwardly convergent position facilitating removal of the blank formed thereon, and a device controlling said means in such manner that the arms are swung in opposite directions and that the first former is located inside the forming vessel when the second former is located outside the forming vessel and vice versa, said position outside the forming vessel of the first former substantially coinciding with the position of the second former outside the forming vessel.

21. In a forming machine for forming blanks of fibres for felt articles, in combination: a stand, a first tapered former and a second tapered former on which formers the blanks are formed, a first pivotable arm and a second pivotable arm pivotably mounted on the stand and on which the first and second formers are respectively mounted throughout the operation of the machine, means for pivoting each arm in a substantially vertical plane between a first position in which the former mounted thereon is at a fibre-receiving station and is upwardly convergent and a second position in which the former mounted on the arm is at a blank removal station and is substantially inverted and downwardly convergent, and means controlling the pivoting movements of said arms in such manner that they are pivoted in opposite directions and that the first former is at its fibre-receiving station when the second former is at its blank removal station and vice versa, said fibre receiving stations of the

formers being coincident and said planes in which the arms are pivoted being symmetrically disposed relative to a third plane when the arms are midway between their first and second positions, a forming vessel consisting of two half-shells which are symmetrically disposed relative to said third plane and are mounted on said stand to be swingable about a substantially vertical axis located on the opposite side of said fibre-receiving station to said pivotal mountings of said arms and disposed substantially in said third plane, the half-shells being swingable between a closed position in which the half-shells surround the former at said fibre-receiving station, and an open position in which the half shells allow the formers to move between said fibre-receiving and blank removal stations.

22. In a machine as claimed in claim 21, comprising means for moving the half-shells between their open and closed positions in cooperation with said means for pivoting said arms and in such manner that the half-

shells are opened to allow the formers to move between said stations and are closed when a former has reached said fibre-receiving station.
